Inventor:
C. L. Horack

UNITED STATES PATENT OFFICE.

CHARLES L. HORACK, OF BROOKLYN, NEW YORK.

AUTOMATIC FIRE-EXTINGUISHER.

SPECIFICATION forming part of Letters Patent No. 313,423, dated March 3, 1885.

Application filed September 12, 1884. (No model.)

To all whom it may concern:

Be it known that I, CHARLES L. HORACK, a citizen of the United States, residing at Brooklyn, in the county of Kings and State 5 of New York, have invented certain new and useful Improvements in Automatic Fire-Extinguishers, of which the following is a specification.

The object of this invention is to construct 10 an automatic fire-extinguisher in such a manner that its outlet be closed by a valve secured in its position by a joint to be broken by the heat of a fire, and that a deflector be brought into a position in front of the outlet or outlets 15 after a fire has broken out, its motion being made to depend upon a spiral spring, which is also adapted to act upon the valve after the deflector has begun to move, thereby keeping said valve free from the influence of said 20 spring until the moment the same is required.

Another object of my invention is to arrange 25 said spiral spring in such a manner, and to place it in such a position, that the same be protected against injurious outside influences which might tend to destroy it, and that after 30 a fire has broken out its lower end may be used for supporting the deflector in a position in front of the outlet.

Another object of my invention is to so construct 35 the device as to permit of removing and again replacing the valve without breaking or interfering with the solder joint.

I attain these objects in the manner illustrated in the accompanying drawings, forming 40 part of this specification.

Figure 1 represents a vertical section, and Fig. 2 a side view, of an automatic sprinkler constructed according to my invention. Figs. 4 and 7 show details, and Figs. 3 and 8 variations, of said device. Fig. 5 represents a vertical section, and Fig. 6 a side view, of another device embodying some of the leading features 45 of my invention.

In Figs. 1, 2, and 4, D represents a discharge-nozzle, forming part of the casting R. The cap-shaped valve V surrounds said discharge-nozzle, and thereby closes the outlets contained therein. The valve V has attached to it by means of screw-thread the cap C, and the latter is supported by the lever L, the lower end 50

of which rests upon a projection on the post M, while its upper end is attached by means of fusible solder to the lug E. The upper edge of the valve V is made to rest against the lead seat l. To firmly seat the valve against 55 said seat, it is only necessary to screw the cap C toward the lever L. x x are upright ribs attached to the inner surface of the distributor. The use of these ribs permits of forming lateral outlets in said distributor by entirely cutting in two said surrounding wall. This, while being easy to construct, would offer the further advantage of allowing the extinguishing-fluid to spread more uniformly 60 than if there were a series of holes cut in said 65 surrounding wall.

S is a spiral spring. The same is inserted from below within the body of the casing R.

O is a cap below said spring. Its outer edge is attached to the casing R by means of 70 screw-thread, while its inner edge is made to form a water and air tight joint where it is made to rest on the lead seat l. The lower part of the wire forming the spiral spring S is bent in such a manner as to move downward through the hole h in the protecting-cap O while the spring S is expanding, and to take hold near its lower end of the deflector P. The extreme lower end of said wire is made 75 to maintain a position directly above the rim 80 r of the cap C, as more fully described herein-after. Said rim r should preferably be given the form of a hexagon to facilitate the taking hold of it when it is desired to tighten the valve by screwing the cap C along the valve 85 V toward the lever L.

It is important to guard the spiral spring S against accidental strokes, as well as against moisture or acids, frequently contained in the air, particularly in manufacturing establishments. For such purpose said spring is entirely surrounded by the outer part of the casing R and the protecting-cap O, except where its lower extension passes through the hole h in said cap O. To effectively close said 90 hole, and at the same time maintain the deflector P in the elevated and protected position shown in Fig. 1 until a fire occurs, I apply fusible solder y between said deflector P and the cap O around the hole h in such a 95 100

manner as to construct there an air-tight joint. It will be seen that thus the coiled part of the spring S is protected absolutely against injurious outside influences. When a fire occurs, 5 the solder joint y will be broken by the heat, and the spring will expand downward, carrying with it the deflector P until the same reaches the position shown in Fig. 2, where one side of it rests on a projection on the post M and the opposite side on the projection a on lug A, the lower part of the wire, forming the spring S, also serving to steady and confine said deflector P. It will readily be seen that by giving the straight part of the wire forming the spring, 10 which is made to pass and slide through the hole h the proper length, the projection a, for supporting the deflector, might be dispensed with. This straight part is located directly opposite one of the ribs x x, so as to least obstruct the distribution of the extinguishing-fluid. The extreme lower end of the wire forming the spring extends below the deflector and to a point somewhat above the rim r of the cap C, as shown in Fig. 1, and it will therefore be seen that no pressure can be exerted 15 by the spring S upon the valve V tending to open it until a fire has actually broken out and the solder joint y, which attaches the deflector P to the cap O, has been broken, there- 20 by allowing the lower extremity of said spring to reach the position occupied before the fire took place by the rim r. It will also be seen that as the lever L, which confines the valve, is held in position by an independent solder joint J, and as the same would fuse as quickly 25 as the one confining the deflector P and the spring S, the lever L, as well as the valve V, with the cap C, owing to their own weight, will always have a tendency to move down- 30 ward in case of a fire, and consequently the action of the spring S, described above, upon the valve V will only take place and be required in exceptional cases, such as sticking of the valve V to its seats, or of the lever L to the points where it is being supported. 35 Fig. 4 represents a horizontal section through the upright ribs x x of the distributor D. It is desirable to have the lateral discharge of the extinguishing-fluid as uniform as possible. 40 If there were simply a number of independent perforations provided in the surrounding wall of the distributor O, a corresponding number of separate and independent streams would be discharged against the deflector, and the distribution of the water would be apt to be particularly copious in front of said perforations. 45 In my distributor, as shown in Figs. 1 and 4, I fully divide in two parts its surrounding wall, but connect these two parts rigidly by means of the upright rib x x. This makes 50 the discharge more uniform, and, besides, is easier to construct. The cross-section of the deflector P, as represented in Fig. 1, shows that the lower part of the same, which is nearest the distributor D, is turned upward. This is done to prevent the escape of too great a

portion of the extinguishing-fluid between the lower edge of the distributor D and said deflector P when the latter has assumed the position shown in Fig. 2.

70

A is a lug attached to the casing R by means of the screw B. Said lug should preferably be made of sheet metal. In Fig. 7, which represents an end view of the same, it is shown how said lug is made to rest on a projection or shoe, E', which forms a part of the casing R. The lever L, which is represented to be made of two thicknesses of sheet metal fastened together, is attached by means of the fusible solder joint J to the lower part of said lug A. The projection f on the casing R, against which it is made to rest on the other side without being soldered thereto, will prevent the solder joint J from being ruptured accidentally, owing to any strokes applied to the lever side- 85 wise.

80

The advantage of using a detachable lug, A, as indicated, is that when it is desired to examine the condition of the distributor D it can readily be done by first taking the strain off of the lever L, (screwing for such purpose the cap C slightly toward the valve V,) and afterward withdrawing the screw B. It will then be possible to remove the lever L with the lug A attached to it without breaking the 95 solder joint connecting the two.

90

Fig. 3 shows a modified construction of the valve closing the outlet and of the lever and of the devices for adjusting the same. Fig. 8 is a side view. In this case I provide a projection, d, on the valve V' to be exposed to the action of the spring S in a similar manner as the rim r is in Fig. 1.

100

To tighten the valve I use the screw G, passing through the lever L'.

105

m and m' represent two lugs attached to the casting R. The pin Z passes through the hanger A', and is made to rest in a horizontal groove on top of said lugs m and m'. The lever L', which is shown to be constructed of two thicknesses of metal fastened together, is attached to the lower part of A' by means of the fusible joints J' and J''. The part of the lever soldered to A' is constructed forking to prevent the accidental knocking off of the 115 same. In this case the lever L, and with it the hanger A', can be detached by either removing the pin Z first, or else, in case said pin should be made fast to the hanger A', by turning the screw G downward, so as to take the strain off of the lever L', and afterward raising the upper end of the lever L', so as to lift the pin Z out of the groove in the lugs m and m', and then swinging the lever L' outward and downward.

120

The depth of the solder-joint J' being much greater than that of J'', it will be seen that shortly after the downward motion of the lever commences, in case of fire those surfaces of A' and L' that are secured to each other by means of the joint J'' will become entirely detached. This will in a great measure do away

125

130

with the danger of the upper edge of L' binding and sticking on A'.

In Figs. 5 and 6 I show another form of a distributor using outlets, each fully dividing 5 in two parts the surrounding walls and ribs x' x', attached to the inner surfaces of said walls and rigidly connecting said parts of said walls. In this case two such outlets are shown, constructed so as to produce intersecting 10 streams. A spiral spring, S, is again inserted within the body of a casting, R, and serves to assist in removing the cap W after a fire has broken out.

In order not to obstruct the distribution of 15 the extinguishing-fluid, I provide two standards, S' and S'', in connection with the spring S. When said spring expands, these standards are pushed upward by the same lifting up the cap W, so as to permit the water to 20 escape freely. I place these standards opposite two of the ribs x' x', so as to least obstruct the discharge of the water. A check, C, is attached to the casing R, as shown in Fig. 5, after the spring has been inserted, so 25 as to prevent its coils from assuming a position in front of the outlets. A lead seat, l', is provided on the casing R, between the spring S and the distributor, for an edge on the valve W to rest on. This will keep the extinguishing-fluid from reaching the spring, as well as 30 the continuous solder joint J'', which attaches the cap W to the casing R until a fire takes place.

I claim as new and wish to secure by Letters Patent—

1. In a distributor for fire-extinguishing purposes, the casing R, in combination with the spiral spring S and the cap O, having an opening therein, as explained, substantially 40 as set forth.

2. The casing R and cap O, in combination with the spiral spring S and the lead seat l, substantially as set forth.

3. In a distributor for fire-extinguishing

purposes, the casing R and cap O, in combination 45 with the spiral spring S, one end of which extends through an opening in said casing, and the deflector P, soldered at y, substantially as set forth.

4. A fluid-distributer for fire-extinguishing 50 purposes provided with a detachable lug for the main fusible joint, whereby said joint may be temporarily removed without breaking the same, substantially as and for purposes set forth.

5. A fluid-distributer, in combination with 55 a valve closing the outlet thereof, a lever supporting said valve, and a detachable lug to which said lever is secured by a fusible joint, substantially as set forth.

6. A fluid-distributer, in combination with 60 a cap-shaped valve screw-threaded on its outer surface, and an auxiliary cap screw-threaded on its inner surface and attached to the valve by said screw-threads, substantially as set forth.

7. The casing R, spring S, and cap O, in 65 combination with the valve V, lead joint l, and lever secured by a fusible joint, substantially as set forth.

8. The casing R, spring S, and cap O, in 70 combination with the valve V, deflector P, lead joint l, and lever secured by a fusible joint, substantially as set forth.

9. A distributor for fluids provided with an 75 annular deflector the edges of whose central opening are turned upward, substantially as set forth.

10. In an automatic fire-extinguisher, a valve held by a fusible solder joint and a 80 spring held by an independent solder joint, a seat for said spring being provided on said valve in the path of said spring, substantially as set forth.
